CLAIM

The ornamental design for a light therapy device for skin care as shown and described herein.

DESCRIPTION

FIG. 1 is a top perspective view of a first embodiment of a light therapy device for skin care.

FIG. 2 is a bottom perspective view of the device of FIG. 1.

FIG. 3 is a front view of the device of FIG. 1.

FIG. 4 is a rear view of the device of FIG. 1.

FIG. 5 is a right side view of the device of FIG. 1.

FIG. 6 is a left side view of the device of FIG. 1.

FIG. 7 is a top view of the device of FIG. 1.

FIG. 8 is a bottom view of the device of FIG. 1.

FIG. 9 is a top perspective view of a second embodiment of a light therapy device for skin care.

FIG. 10 is a bottom perspective view of the device of FIG. 9.

FIG. 11 is a front view of the device of FIG. 9.

FIG. 12 is a rear view of the device of FIG. 9.

FIG. 13 is a right side view of the device of FIG. 9.

FIG. 14 is a left side view of the device of FIG. 9.

FIG. 15 is a top view of the device of FIG. 9; and,

FIG. 16 is a bottom view of the device of FIG. 9.

The broken lines in the drawings illustrate portions of the light therapy device for skin care that form no part of the claimed design.
